TROUSETTES

Ada L. Westfall, Jacksonville, Fla.

Application March 4, 1947, Serial No. 732,149

2 Claims. (Cl. 2—224)

1

My invention relates to garments, and particularly to those under garments which are worn about the lower part of the body, from the waist downward to a point between the crotch and the knee, and which are commonly known as panties or trousettes. The object of my invention is to provide a garment which may be made at low cost; but which at the same time shall be comfortable to the wearer in both erect and stooping positions.

In the drawings, which form a part of this specification: Figure 1 is a front view in elevation of the completed trousette. Figure 2 is a side view of the same. Figure 3 shows the front gore in elevation. Figure 4 shows the front leglet as cut out. Figure 5 shows the front leglet joined to the bottom of the front gore. Figure 6 shows the rear gore as cut out. Figure 7 shows the rear left leglet; and Figure 8 the rear right leglet.

In the several figures: the V's shown as cut in the edges of the several parts of the garment, as at 2, 4, 6, are used to indicate how and where certain parts are to be fitted together. For instance: a point marked with three V's on one part is aligned with a point also marked with three V's on another part; or a point marked with one V on a part is aligned with a point marked with one V on another part.

The several parts of my trousette having been cut out: I assemble them and join them together, usually by means of a flat seam; reinforcing those seams which are likely to be subjected to strain by means of a tape sewn down on the seam. After joining the several parts together, the free edges may be finished by a whipped hem.

I cut the rear gore as shown in Figure 6. It is trapezoidal in shape, with its upper edge shorter than its lower edge; and with its lower edge oppositely and concavely curved a little downward from each end of the gore toward the center line of the gore and to a place adjacent to it.

In the drawing, Fig. 6, the space between the adjacent ends of the two curves 12 and 14 is indicated by a line p. This line may be nearer to or farther from a line joining the two bottom corners of the rear gore, depending upon the size of the garment.

Darts 8, 8, are cut in the ends of the rear gore, and when the edges of each dart are sewn together the rear gore will be given a fullness.

The left and the right rear leglets, 18 and 20, Figs. 8 and 7 are cut in the form of a trapezium, in which no two sides are equal in length. The lower edge in Fig. 8 and also in Fig. 7 is longer than the upper edge, and one end is longer than

the other. These two rear leglets are alike in shape; but one is the reverse of the other. To shape the rear gore 10: I close the darts 8, 8; sewing their edges together. I then join the upper edge of the left rear leglet 18, and the upper edge of the right rear leglet 20, to the bottom edges 12 and 14, respectively, of the rear gore 10; arranging the shorter end of each leglet in line with the adjacent end of the rear gore.

10 The length of the upper edges of the two leglets 18 and 20 is such that when sewn to the bottom of the rear gore 10 there will be a space, indicated by the line p, between them.

The front gore is shorter than the rear gore. 15 It also is trapezoidal in form; its lower edge being slightly longer than its upper edge. These two edges are preferably slightly concave. The two ends of the front gore are slightly convex. The depth of the two ends is substantially equal to the shortened ends of the rear gore when the darts 8, 8 have been closed. To the ends of the rear gore the ends of the front gore are sewn; that is to say: the two ends 42 and 44 of the front gore are sewn to the two ends 46 and 48, 20 respectively, of the rear gore.

The front leglet is indicated by the numeral 26 25 in Fig. 4. I have here the right and left front leglets; but they are cut in one piece. This piece: bounded by the base m—n, the convexly curved sides s and t, and the ends 29 and 30; is slotted 30 on its vertical center line, the slot having curved sides 32 and 34. At the bottom of the slot the ends of the two sides 32 and 34 may come together or they may be separated by a short space 35 as indicated by the line 36 in Fig. 4. This again depends upon the size of the garment.

I now take the front leglet 26, and open the ends 29 and 30 of the leglet until the sides 32 and 34 of the slot are in line; and I then register 40 the inner edge of the leglet formed by the slot sides 32 and 34 with the base line 38 of the front gore 40, and sew them together (Fig. 5). The front leglet 26 now forms the right and the left front leglets 27 and 28, seen in Fig. 5.

45 Because the lower edges u and v of the left and the right rear leglets 18 and 20 are longer than the upper edges of the same; and because the outer edges s and t of the front leglet 26 are longer than the inner edges of the slot in the said leglet; the outer edges of the several leglets 50 when assembled in the garment will have the loose and wavy line shown in Fig. 5, instead of a tight line fitting closely to the thighs; an advantage when the wearer stoops or sits.

The lengths of the small ends of the rear leg-

lets 18 and 20 are substantially equal to the lengths of the free ends 29 and 30 of the front leglets 27 and 28; and the former are sewn, one to each of the latter.

There now remain free, at the lower part of the trousette, the following edges: the edge $m-n$ of the front leglet 26 (Figure 4); the edge p of the extension 16 of the back gore 10; and the edges q and r of the rear leglets 18 and 20 respectively. These three edges p , q and r are together equal in length to the edge $m-n$ of the front leglet 26; and, being arranged in line, they are joined to the said edge $m-n$ of the front leglet 26.

The trousette is now complete, except for the waistband, which is placed along the top edges w and x of the front gore 40 and the back gore 10, respectively. This waistband may be of any suitable type, preferably elastic.

I claim:

1. A trousette comprising a rear gore, a front gore, a left hand rear leglet, a right hand rear leglet, and a front leglet; the rear gore being of greater length than depth, trapezoidal in shape and with its upper edge shorter than its lower edge, the said lower edge being oppositely and concavely curved downward from the ends of the gore toward the center, the said gore having darts cut in each end, the edges of each dart being sewn together to shorten the ends of the gore to give it fullness; a front gore substantially trapezoidal in shape, shorter in length than the rear gore, with inwardly curved upper and lower edges and with outwardly curved end edges, the said end edges being substantially equal in length to the shortened ends of the rear gore to which they are respectively sewn; a front leglet piece in plan having a substantially straight base line and convexly curved sides, the said leglet piece being slotted vertically on the center line, which slot along its edges will equal in length the lower edge of the front gore to which edge the said inner edges of the slot in the front leglet are sewn; a left rear leglet being in shape a trapezium having a longer bottom edge than upper edge and one end longer than the other end, the said leglet being sewn by its upper edge to the curved lower left edge of the rear gore and with its longer end adjacent the center line of the rear gore; a right rear leglet being in shape a trapezium having a longer bottom edge than upper edge and one end longer than the other end, the said leglet being sewn by its upper edge to the curved lower right edge of the rear gore and with its longer end adjacent the center line of the rear gore, the said left and right rear leglets being so arranged

with respect to the rear gore that the longer ends of the two leglets with that part of the lower edge of the rear gore which lies between them will form an edge which substantially equals in length the base line of the front leglet piece and is sewn thereto; and the free ends of the said front leglet piece are sewn one to each of the shorter and free ends of the right and left rear leglets.

2. A trousette comprising a rear gore having greater length than depth, its lower edge being oppositely curved downward from the ends of the gore toward the center, the said gore having darts cut in each end the edges of each of which darts are sewn together; a front gore shorter in length than the rear gore with a concavely curved lower edge, and with end edges substantially equal in length to the shortened ends of the rear gore to which they are respectively sewn; a front leglet piece in plan having a base line and convexly curved sides, the said leglet piece being slotted vertically on its center line the edges of the slot being equal in length to the lower edge of the front gore to which they are sewn; a left rear leglet having a longer bottom edge than upper edge and one end longer than the other end, the said leglet being sewn by its upper edge to the curved lower left edge of the rear gore with its shorter end registering with the left end of the rear gore; a right rear leglet having a longer bottom edge than upper edge and one end longer than the other end, the said leglet being sewn by its upper edge to the curved lower right edge of the rear gore and with its shorter end registering with the right end of the rear gore; the said rear leglets being so arranged with respect to the rear gore that the longer ends of the two leglets with that part of the lower edge of the rear gore which lies between them will form an edge which substantially equals in length the base line of the front leglet piece and is sewn thereto; and the free ends of the said front leglet piece being sewn one to each of the shorter and free ends of the right and left rear leglets.

ADA L. WESTFALL.
